UNITED STATES PATENT OFFICE.

STANLEY LESZCZYNSKI AND ANTHONY LESZCZYNSKI, OF GARY, INDIANA.

GARMENT.

1,291,942

Specification of Letters Patent. Patented Jan. 21, 1919.

Application filed April 14, 1917. Serial No. 162,012.

To all whom it may concern:

Be it known that we, STANLEY LESZCZYNSKI and ANTHONY LESZCZYNSKI, citizens of the United States, residing at Gary, in the county of Lake and State of Indiana, have invented certain new and useful Improvements in Garments; and we do hereby declare the following to be a full, clear, and exact description of the invention, such as will enable others skilled in the art to which it appertains to make and use the same.

This invention relates to garments and more particularly to that class of garments known as union suits.

15 One of the aims of this invention is to provide a garment formed of pieces cut from the material in such a manner as to eliminate the necessity of the employment of gores and the like or elastic inserts in various parts of 20 the garment to strengthen or provide the necessary elasticity to the garment as is now the common practice.

Another aim of this invention is to so cut the parts of the garment from the material 25 that the garment made therefrom will be strong and durable and possessed of the necessary elasticity to readily yield to the movements of the body of the wearer and at the same time to provide a garment that is 30 comfortable to the wearer.

Another aim of this invention is to so cut the garment from the material as to require but few parts to construct the garment and with practically no waste of the material.

35 These and other objects and advantages will more fully appear as the nature of the invention is more clearly understood from the method of constructing and the assembling of the parts of the garment as described 40 in the following specification, defined in the subject matter of the claims, and the views illustrated in the accompanying drawings, in which.

Figure 1 is a front view of the garment.

45 Fig. 2 is a rear view thereof.

Fig. 3 is a front view of the garment showing the leg portions in oppositely extended positions.

Fig. 4 is a plan view showing the method 50 of cutting the parts of the garment from the material.

Fig. 5 is a view of the parts of the garment after the same has been cut and previous to the assembling of the parts.

55 As the garment is formed of correspond-

ing parts, made however in rights and lefts, the corresponding parts will be designated by the same reference characters.

Referring to the drawings 1 denotes the rear sections of the garment, provided with 60 the meeting and overlapping edges 2, the crotch and seat portions 3, and the leg portions 4, the outer edges of the sections 1 being denoted by the numeral 5 and the inner edges of the sections 1 being denoted by the 65 numeral 6.

Stitched or otherwise secured to the upper edges of the sections 1 is the yoke 7, which is designed to cover the upper portion of the back and the shoulders of the wearer, the 70 yoke 7 being provided with a portion of the arm hole 8 and the neck portion 9, the yoke 7 being also provided with the side edges 10 so that when the yoke 7 is secured upon the sections 1 the side edges 10 of the yoke 7 75 will be in alinement with the outer edges 5 of the sections 1. The foregoing constitutes the rear half of the garment.

The front half of the garment consists of two parts comprising the body portions 11 80 and the leg portions 12. These parts are provided with the side edges 13 which are stitched or otherwise secured to the edges 5 of the sections 1 and to the edges 10 of the yoke 7, and above the side edges 13 of these members are formed the other arm hole portions 14, which in conjunction with the arm-hole portions 8 of the yoke 7 form the arm holes of the garment when the upper edges 15 of the front members are stitched or otherwise secured to the edges 16 of the yoke 7, the sloping edges 17 completing the neck of the garment in conjunction with the neck portion 9 of the yoke 7. The edges 18 of the front members or sections are stitched or 95 otherwise secured to the edges of the crotch or seat members 3 and the edges 6 of the leg members 4 of the rear sections 1, so that the leg portions 4 of the rear sections 1 and the leg portions 12 of the front sections 11 form 100 the legs of the garment, the front sections 11 being provided with the meeting and overlapping edges 19 at the front of the wearer.

The garment is provided with the sleeves 20 which are formed with the converging 105 side edges 21 which are stitched or otherwise secured together, and are further provided with the curved inner edge 22 so as to adapt the edge 22 to be stitched or otherwise secured to the armholes of the gar- 110

ment which are formed by the armhole portions 8 and 14 respectively of the yoke 7 and the front sections 11.

When assembling the respective parts of the garment it is preferable not to secure the edges 5 of the sections 1 and the edges 13 of the front sections 11 for their entire length, but to terminate the securing together of these edges at a point slightly remote from the lower ends of the leg portions of the garment and to face the lower edges of the leg portions of the garment with the bands 23, so that, the lower ends of the leg portions of the garment may be retained in snug engagement with the leg of the wearer by overlapping the portions 24 that are provided upon the leg portions 4 of the rear sections 1 upon the adjacent portions of the leg portions 12 of the front sections 11 and securing the portions 24 thereon by means of the buttons 25 or other suitable securing means, and it is desirable to secure together the overlapping meeting edges 2 of the rear sections 1 by the button 25 and buttonhole 26 or other suitable securing means, and to also secure together the overlapping meeting edges 19 of the front sections 11 through the medium of the buttons and buttonholes 27 or other suitable securing means.

From the foregoing it will be seen that by cutting the parts of the garment from the sheet of material 28, as clearly shown in Fig. 4, we are enabled to provide a garment requiring only seven parts formed in such a manner that the parts, especially the parts constituting the rear sections 1, will be so formed with respect to the warp and weft threads of the material that the same will possess the necessary flexibility or yieldability to accommodate the various movements of the body of the wearer without the necessity of employing gores or gussets

or inserts of any nature to provide the necessary elasticity to the garment as is now indispensable in the construction of the garments now upon the market, and at the same time by this method the cutting of the parts of the garment out of the material is made possible with an exceedingly minimum amount of waste and, therefore, the garment can be more cheaply produced.

Having described our invention, what we claim as new and desire to secure by Letters Patent, is:—

1. The method of producing a union garment consisting of cutting from a strip of material the back sections extending lengthwise of the warp thereof in reverse position, and cutting the front portions of the garment in parallel positions extending lengthwise of the warp of the material beyond the body portion of the back sections.

2. The method of producing a union garment consisting of cutting from a strip of material the back sections extending lengthwise of the warp thereof in reverse position, cutting the front portions of the garment in parallel positions extending lengthwise of the warp of the material beyond the body portion of the back sections, cutting the yoke section from the material at the opposite end of said body portion from the front sections, and cutting arm sections in parallel positions extending with the weft of the material at one side of the front section.

In testimony whereof we have signed our names to this specification in the presence of two subscribing witnesses.

STANLEY LESZCZYNSKI,
ANTHONY LESZCZYNSKI.
